SUCTION CLEANER

Charles G. Troxler, North Canton, Ohio, assignor
to The Hoover Company, North Canton, Ohio,
a corporation of Ohio

Application December 23, 1940, Serial No. 371,290

2 Claims. (Cl. 306—13)

The present invention relates to suction cleaners in general and more particularly to new and novel improvements in handle constructions for suction cleaners. More specifically the invention comprises a hand grip construction which supports a switch and means for actuating a handle control mechanism.

It is an object of the present invention to provide a new and improved hand grip for a suction cleaner handle. Another object is to provide a hollow hand grip construction formed from a U-shaped member and a cover plate. A further object is to provide a hand grip construction wherein the U-shaped member and cover plate cooperate to rotatably support a finger operated lever to actuate a handle control mechanism. These and other objects of the invention will be apparent from the following specification and drawing, wherein:

Figure 1 is a side elevation of a suction cleaner embodying the present invention;

Figure 2 is a section through the hand grip construction, and

Figure 3 is a section along the line 3—3 of Figure 2.

The embodiment of the invention disclosed in the drawing comprises a suction cleaner having a main casing 10 supporting a motor housing 11. Within the casing 10 is provided a nozzle, a fan chamber and an exhaust outlet, all operatively connected in a manner well known in the art. An unshown motor is positioned within the housing 11 and drives a suction-creating fan within the fan chamber to remove dirt from the surface being cleaned and exhaust the dirt into a filter bag 12 attached to the exhaust outlet. The cleaner is supported on front and rear wheels 13 and 14, respectively.

Pivottally mounted on the casing 10 is a handle socket 15 for removably supporting a handle 16. The handle comprises an elongated hollow metallic tube 17 provided at its upper end with a hand grip 18. The hand grip is formed from a substantially U-shaped metal insert 8 having its bight portion 19 forming a continuation of the top of the hollow handle 17 and having depending side walls 20 and 21 which define an elongated open mouth at the under side of the hand grip 18. This opening is closed by a removable cover plate 22 formed from a plastic or other electric insulating material. The U-shaped metal insert is also provided with an exterior coating of plastic or other insulating material.

The U-shaped metal hand grip 8 is rigidly attached to the upper end of the tubular handle 17

5 by means of rivets 25, only one of which is shown. The top wall 19 of the metal hand grip is provided with sections 26 and 27 partially punched out from the major portion of the top wall 19 to form pairs of seats 9, 9 and 29, 29, respectively. Welded on to the section 26 is a bracket 30 having a platform surface 31 and feet 32, 32 which bear against the seats 9, 9 to form a good anchorage for the bracket. Another bracket 33 is welded to the section 27 and is provided with a platform surface 34 and feet 35, 35 which abut the seats 29, 29 to position the bracket during the welding process and aid in anchoring it in position.

10 In attaching the hand grip cover plate 22 to the U-shaped member 8, projections 37, 37 on the cover plate bear against the platforms 31 and 34, respectively, and screws 38, 38 are threaded into the bracket to rigidly hold the cover plate in position.

15 The hollow interior of the hand grip accommodates and supports a switch 40 and a mechanism for actuating a handle control device. The actuating mechanism comprises an elongated metal bar 41 which is slidably supported in channels 42 in the arms 44 of the bracket 33. A lever 45 is pivotally supported in a recessed portion 46 of the bracket 33 and a cooperating recess 47 in the hand grip cover plate 22. One end 48 of the lever 45 is connected to the elongated bar 41 and the opposite end 49 is adapted to be manipulated by the hand of the operator to actuate the handle control mechanism indicated generally at 50, whereby the handle may be moved to different positions.

20 25 The switch 40 is also supported in the U-shaped metal member 8 by resting against the cover plate 22 and a rubber washer 51 seated about a projection 52 in the top wall 19 of the metal member 8. An opening 55 is provided in the cover plate 22 through which the switch lever 56 projects to the under side of the handle. Electric conductors 57 extend from the switch 40 downwardly in the handle to the unshown motor.

20 25 30 35 40 45 50 55 60 65 70 75 80 85 90 95 Also supported by the hand grip cover plate 22 is a strain relief member 60 for an electric cord which is connectible to a source of current. The strain relief member 60 includes a sleeve portion 61 which projects through an opening in the hand grip cover plate and is channeled at 62 to receive tines 63 of an angle shaped forked member 64 which rests against the inner surface of the hand grip cover plate to hold the strain relief member against displacement. The forked member 64 has a shoulder 65 at one end which

serves as a grip to remove the member 64 when it is necessary to replace the strain relief member 60.

The top end of the filter bag 12 is supported by a spring 66 suspended from a hook 67 resting against the hand grip cover plate and is secured thereto by a screw 68 threaded through the handle 17 into a plate 70 welded to the side walls of the U-shaped metal member 3.

From the foregoing it will be perceived that the handle control actuating mechanism is completely supported between two separable parts of the hand grip, and that the cord strain relief member 60 is also held in position between the two separable parts of the hand grip.

I claim:

1. In a suction cleaner, a handle pivotally mounted on the body of said cleaner, handle control means including a rod slidably mounted in said handle for controlling the positions of said handle relative to the cleaner body, a hand grip at the upper end of said handle and comprising a substantially U-shaped member having a cavity and an open mouth, a bracket in said cavity mounted on said U-shaped member

for slidably supporting said rod, a removable cover for closing said open mouth, means for actuating said rod, a recess on said bracket means, a recess in said cover cooperating with said first-mentioned recess to provide a walled chamber for pivotally supporting said actuating means.

2. In a suction cleaner, a cleaner body, a handle pivotally mounted on said body, handle control means for controlling the positions of said handle relative to the cleaner body, means for actuating said control means, a hand grip formed in cooperating sections attached to the upper end of said handle, means on one of said hand grip sections defining a substantially semi-circular recess, another of said hand grip sections having a substantially semi-circular recess cooperating with said first mentioned recess to provide an annular walled chamber to pivotally support said actuating means, said semi-circular recess being at the meeting surfaces of said hand grip sections to form said annular walled chamber transversely of said hand grip at said meeting surfaces.

25

CHARLES G. TROXLER.
